(57) CLAIM

We claim, the ornamental design for a display screen portion with icon, as shown and described.

DESCRIPTION

FIG. 1 is a front view of a display screen portion with icon showing our new design according to a first embodiment; and, FIG. 2 is a front view of a display screen portion with icon showing our new design according to a second embodiment. The broken line showing of a display screen portion with icon is included for the purpose of illustrating portions of the article that forms no part of the claimed design.

1 Claim, 2 Drawing Sheets

FIG. 2
